UNITED STATES PATENT OFFICE.

LOUIS DAVIS AND HERMAN HENDRIKS, OF LONDON, ENGLAND.

CIGARETTE-MAKING MACHINE.

SPECIFICATION forming part of Letters Patent No. 662,775, dated November 27, 1900.

Application filed November 21, 1899. serial No. 737,727. (No model.)

To all whom it may concern:

Be it known that we, LOUIS DAVIS and HERMAN HENDRIKS, subjects of the Queen of England, residing at London, England, have invented certain new and useful Improvements in or Relating to Cigarette-Making Machines, (for which we have made application for Letters Patent in Great Britain, No. 8,636, dated April 25, 1899, and No. 22,152, dated November 6, 1899,) of which the following is a specification.

This invention relates to improvements in cigarette-making machines, and is especially applicable to that type of machine known as a "continuous-cigarette" machine.

The invention consists in the novel construction, arrangement, and combination of parts, as hereinafter fully described, illustrated in the drawings, and pointed out in the appended claims.

The invention will be best understood by reference to the accompanying drawings, in which—

Figure 1 is a plan of one construction of a complete cigarette-machine according to this invention. Fig. 2 is a central vertical section of the same. Fig. 3 is an end elevation of the machine looking toward the left in Fig. 1. Fig. 4 is an end view of the cutting mechanism. Fig. 5 is a separate plan view of the pasting device; Fig. 6, a central vertical section of the same. Fig. 7 includes a plan and an end view of the blade employed in the folder. Fig. 8 is a plan of the folder; and Fig. 9, a series of sections through the folder along lines A A, B B, C C of Fig. 7.

Like letters indicate like parts throughout the drawings.

The various mechanisms are disposed along the bed-plate A of the machine, supported upon standards A', which may be secured to the floor. The tobacco disintegrating and feeding mechanism is mounted in a framework A², bolted to the bed-plate A. The tobacco is first placed upon a conveyer-band B, which travels over pulleys B' B², the pulley B² being mounted between the standards B³. A plain roller B⁴ is mounted in the framework A² in close proximity to the pulley B' and serves to roll the tobacco evenly as it passes over the end of the conveyer-band B. A second plain roller B⁵ revolves in an oppo-

site direction to the pulley B' and draws the tobacco from between the plain roller B⁴ and conveyer-band B, delivering it to a combing or picking roller B⁶, which revolves in the same direction as the pulley B', but at a much higher rate of speed. By the action of the picking-roller B⁶ the tobacco is torn into fine shreds. It then falls into an oscillating hopper B⁷ in a finely divided or disintegrated condition. The oscillating hopper B⁷ is pivotally supported upon the extremities of the axle of a large pin-roller B⁸, mounted in the framing A², by means of segment-pieces B⁹, the bottom of the hopper being virtually constituted by the pin-roller B⁸, which revolves slowly in the same direction as the combing-roller B⁶. A plain roller B¹⁰ is mounted between the ends of the hopper B⁷, just out of contact with the pins of the roller B⁸, so that the tobacco falling onto the roller B⁸ will be uniformly distributed and packed between the pins thereof by the combined oscillating action of the hopper B⁷ and roller B¹⁰.

B¹¹ is a second high-speed picking or combing roller, the pins of which, intercalating with the pins of the roller B⁸, tear the tobacco from between the pins of the large roller B⁸, thereby effecting the final and complete disintegration of the tobacco, which then falls into a hopper B¹² and is delivered onto a traveling band C, by which it is conveyed to the next mechanism.

The means for operating the feeding and disintegrating mechanism are as follows: A spur-pinion A¹⁴ upon the main driving-shaft A³ drives, through the medium of a spur-wheel A¹⁵, sprocket-wheel B¹³, and chain B¹⁴, a sprocket-wheel B¹⁵, the latter being keyed to one end of a small counter-shaft B¹⁶. Upon the opposite end of the counter-shaft B¹⁶ is keyed a bevel-pinion B¹⁷, which drives the pulley B' through the medium of bevel-pinions B¹⁸, B¹⁹, and B²⁰. Upon the opposite extremity of the axle of the pulley B' is keyed a spur-pinion B²¹, which communicates motion to the rollers B⁵ and B⁴ through the medium of other spur-pinions B²² B²³. The large pin-roller B⁸ is driven from the pulley B' through the medium of the sprocket-wheel B²⁴, keyed to the extremity of the axle thereof, chain B²⁵, and sprocket-wheel B²⁶, keyed to the extremity of the axle of the pin-roller

B⁸. The high-speed combing or picking roller receives motion from the main shaft A³ through the medium of a sprocket-wheel B²⁷, keyed upon the latter, sprocket-chain B²⁸, sprocket-wheel B²⁹, spur-wheel B³⁰, and spur-pinion B³¹, Fig. 2, keyed upon the extremity of its axle. The lowermost high-speed picking-roller is driven in a similar manner through the medium of a sprocket-wheel B³², sprocket-chain B³³, sprocket-wheel B³⁴, spur-wheel B³⁵, and spur-pinion B³⁶. The oscillation of the hopper is effected by an eccentric B⁴⁰, keyed to the main driving-shaft A³, which reciprocates an eccentric-rod B³⁸, coupled to an arm B³⁹, secured to the hopper.

The operation of this mechanism is as follows: The tobacco being placed upon the conveyor B will be evenly rolled and fed to the combing-roller B⁶ by means of the plain rollers B⁴ and B⁵. The high speed of the combing-roller B⁶ effects a very fine disintegration of the tobacco, which falls into the oscillating hopper B⁷ and is uniformly distributed and evenly packed over the pin-surface of the roller B⁸, owing to the action of the hopper and its roller B¹⁰. The tobacco is finally and completely disintegrated by the second high-speed picking-roller B¹¹, the pins of which intercalate with those of the roller B⁸. The tobacco in a thoroughly-disintegrated condition falls into the hopper B¹² and is delivered to the traveling band C. The endless traveling band C conveys the tobacco from beneath the hopper B¹² to the compressing and filler-forming mechanism. The band C travels upon two pulleys C' C², one of which, C', is mounted in a carriage arranged to slide upon a bracket C³, bolted to the end of the bed A, a hand-wheel and screw C⁴ being employed to shift the carriage to adjust the tension of the band. The other pulley C² is mounted between supports A⁶ of a table A⁷, the supports A⁶ being bolted to the bed-plate A. The band C travels over a grooved platform A⁸ from the hopper B¹² to the pulley C², the cross-sectional dimensions of the band being slightly smaller than those of the groove. Flange-pieces A¹² are secured upon either side of the groove, so as to form a trough from the hopper B¹² to a compressing-roller C⁶, the bottom of the trough being constituted by the band C. As will be seen, the width of the trough is much less than the width of the band C and is very slightly greater than the width of the reduced portion C⁵ of the compressing-roller C⁶. The tobacco is carried by the band C beneath the roller C⁶ and is compressed vertically upon the band between the roller and the rigid platform A⁸. The roller C⁶ is mounted between brackets A¹³, screwed to the platform A⁸. The tobacco is next compressed by a pair of endless metallic traveling bands C⁷ C⁷, which are caused to pass around horizontal pulley-wheels C⁸ C⁹ C¹⁰ C¹¹. Two of these pulley-wheels—viz., C⁸ C¹⁰—are keyed to vertical spindles C¹² C¹³, journaled in bosses formed upon the bed A of the machine, and are driven, while the other

two wheels C⁹ C¹¹ are free to rotate about pins C¹⁴ C¹⁵, adjustably secured in the table A⁷. The adjusting-screws C¹⁶ C¹⁷ enable the wheels to be shifted when it is desired to increase or decrease the tension of the bands C⁷ C⁷. The wheels C⁸ C¹⁰ are mounted with but a slight space intervening between their peripheries. The wheels C⁹ C¹¹, however, are situated much farther apart. The tobacco is conveyed by the band C into a gradually-converging channel between the metallic bands C⁷ C⁷, which compress it laterally and carry it forward. The bottom of the channel is constituted by the table A⁷, one end of which is in close proximity to the point at which the tobacco leaves the traveling band C, the bands C⁷ C⁷ commencing their compressing action upon the tobacco approximately at the same spot. The space between the bands C⁷ C⁷ and the compressing-roller C⁶ is entirely inclosed by means of flange-pieces C¹⁹, secured to the platform A⁸ and supporting between them a top cover-plate or apron C²⁰, shaped so as to fit between the wheels C⁸ C¹⁰. The flanges C¹⁹ and cover-plate C²⁰ keep the tobacco from expanding after having been rolled by the roller C⁶. The tobacco is conveyed by the compressing-bands C⁷ C⁷ to grooved filler-forming rollers C²¹ C²², arranged one over the other, with their grooved peripheries in close proximity, so as to form a circular or similarly-shaped passage or opening between them. The tobacco passing through such passage or opening is finally formed into a filler or rod of the required shape and dimensions and is ready to receive its paper wrapping.

The pulley C², over which the belt C runs, is keyed to a shaft C³³, set at right angles to the main shaft A³. This shaft C³³ receives its motion from the main shaft through the medium of bevel-wheels C²³ C²⁴, spindle C²⁵, spur-wheel C²⁶, and spur-pinion C²⁷, the latter being keyed to the main shaft A³. The compression-roller C⁶ is driven from a grooved wheel C³⁴, keyed to the spindle of the driven pulley C', by means of a crossed belt which runs over a grooved wheel C³⁵, secured upon the axle of the roller C⁶. To the lower extremities of the vertical spindles C¹² C¹³ of the wheels C⁸ C¹⁰ are keyed bevel-wheels C²⁸ C²⁹, which gear with other bevel-wheels C³⁰ C³¹, keyed to the extremities of a shaft C³², which is driven from the shaft C³³ through the medium of spur-wheels C³⁴ C³⁵ C³⁶. The bands C⁷ C⁷ are caused to run parallel up to the grooved rollers C²¹ C²² by means of the friction-rollers C³⁷, after passing which the bands diverge, owing to the distance between the peripheries of the wheels C⁹ C¹¹. The grooved rollers C²¹ C²² are driven from the shaft C³³ through the medium of spur-wheels C⁴⁰, C⁴¹, C⁴², and C⁴³.

The operation of the compressing and filler-forming mechanism is as follows: The tobacco is carried by the band C beneath the roller C⁶, as hereinbefore described. The roller C⁶ compresses the tobacco in a vertical

direction, and it then proceeds to the compressing-bands C⁷ C⁷, passing from off the band C onto the table A⁷. The bands C⁷ C⁷ compress the tobacco laterally and deliver it 5 to the grooved filler-forming rollers C²¹ C²², which finally form the tobacco into a filler or rod of the required shape and size and deliver it to the mouthpiece of a folding device.

The folding device E and its mouthpiece 10 E' are secured to a long narrow platform A⁹, supported upon uprights A¹⁰, bolted to the bed A. The mouthpiece E' is constituted by a plate formed with a tapering groove E², the width of the groove at the entrance being 15 most equal to the width of the paper wrapper F and narrowing down to a semicircle in cross-section. Spring-blades E³ are situated within the groove E² and serve to guide the tobacco rod and to cause the paper F and a 20 canvas tape F', supporting it, to conform to the shape of the groove E². The spring-blades E³ also prevent the paper from buckling. A convex presser-blade E⁴ is situated within the groove E² and serves to press upon 25 the tobacco filler or rod and prevent it from expanding. This blade is secured to the top of the plate E' by means of its shank E⁹.

The folder E comprises two plates E¹⁰ E¹¹, Figs. 8 and 9, each provided with a longitudinal groove. When the plates E¹⁰ E¹¹ are placed together, the grooves register with each other and form a circular passage E⁵, through which the tobacco rod and its wrapper travel. The top plate E¹⁰ is divided longitudinally 35 into two portions, such portions being situated slightly apart, so that a longitudinal slit E⁶ is formed for a purpose hereinafter described. The slit E⁶, as will be seen in Fig. 8, is along one side of the circular passage E⁵ 40 for a part of its length and along the opposite side for the remainder of its length. A loop-shaped aperture E⁷ is formed at or near the center of the plate, said aperture being the junction for the two portions of the slit. 45 Within the aperture E⁷ a curved blade E⁸, Figs. 8 and 9, is placed. This blade E⁸ is attached to the top plate E¹⁰ of the folder E. The endless canvas tape F', which supports 50 the paper throughout the folding operation, is driven by the rollers F² F³. The tape F' after leaving the mouthpiece E' and folder E opens out flat and travels along the narrow platform A⁹ to the end thereof, where it passes around a friction-roller F⁴ and arrives at the 55 rollers F² F³, being lapped over the first roller F² and underneath the second roller F³. The tape passes from these driving-rollers over an idle roller F⁶ and then beneath a tension-roller F¹³, which is mounted in vertical slots 60 in the brackets F⁶, so that such tension-roller F¹³ may be adjusted to take up any slackness of the tape F'. The tape passes around a second friction-roller F⁷ at the opposite end of the platform and arrives again at the mouthpiece 65 of the folder. A small space A¹¹ separates the end of the platform A⁹ from the edge of the table-plate A⁷, and through such space the

paper strip F and canvas tape F' are passed. The paper is supplied by a roll F⁸ beneath the machine and is led through printing mechanism G, if desired, around a friction-roller F⁹ and upward over the roller F⁷, where it meets with the canvas tape F' and passes with the tape into the mouthpiece E'. The roller F² is keyed to a spindle F¹⁰ at right angles to the 70 main shaft and driven therefrom by the bevel-pinions F¹¹ F¹². The motion received by the roller F² is transmitted to the roller F³ through the spur-wheels F¹³ F¹⁴, keyed to the axes of the rollers. In Fig. 2 the paper is 80 shown broken off at X, it not being shown in the mouthpiece and folder for sake of clearness.

The operation of the mouthpiece E' and folder E is as follows: The paper and canvas 85 tape enter the mouthpiece E', and as the narrow end of the groove E² is approached they are formed into a channel, in the bottom of which lies the tobacco filler. Upon entering the circular passage in the folder E corresponding edges of the paper and tape are 90 folded over, as shown in Fig. 9, section A, the opposite edges of the paper and tape remaining upright and passing along the slit E⁶ between the two portions of the top plate. 95 The paper projects through the slit above the surface of the plate and is pasted by a pasting device hereinafter described. The curved or convex blade E⁸ serves both to separate the folded edge of the canvas tape 100 from the folded edge of the paper and also to press upon the tobacco and keep it from expanding as it passes beneath the opening E⁷. After having been lifted by the blade the edge of the canvas tape passes along the 105 portion of the slit upon its side of the passage E⁵, the opposite and pasted edge of the paper, together with the corresponding edge of the canvas band, being folded down over the under lap or edge by contact with the inclined edge E¹² of the aperture E⁷. The pressure to which the pasted edge is subjected during the passage of the cigarette through the remainder of the folder serves to effectively seal the freshly-made joint. After 110 emerging from the folder the continuous length of cigarette is carried toward the cutting mechanism upon the endless tape F'.

Referring to Figs. 5 and 6, the paste-pot H is carried upon a base-plate H' and is provided with a weighted piston H² to force the paste onto a pasting-wheel H³. A screw H⁴, passing through the lid H⁵, may be turned by a hand-wheel if it is desired to increase the pressure of the piston upon the paste. 120 The paste-wheel H³ is rotatably mounted upon a vertical spindle H⁶ and is situated partly within the paste-reservoir H. Scrapers H⁷ for the top and bottom surfaces of the pasting-wheel are adjusted by means of the 125 screws H⁸ to such a pressure as to prevent any paste from leaving the roller upon either of such surfaces. The pasting edge H⁹ of the wheel is slightly beveled, and the amount 130

of paste thereupon may be varied by means of the scraper H^{10} , operated by means of a screw H^{11} . The spindle of the paste-wheel receives its motion from the spindle F^{10} , which 5 drives a sprocket-wheel H^{12} , keyed upon a spindle H^{13} , which gears with the paste-wheel spindle H^6 through the bevel-pinions $H^{14} H^{15}$. Within the paste-pot H are three vertical grinding-rollers $H^{17} H^{18} H^{19}$, the axes of which 10 project through the base of the paste-reservoir and have keyed upon their extremities spur-pinions $H^{20} H^{21} H^{22}$. The spur-wheel H^{20} is of such a depth as to permit of the pinions $H^{21} H^{22}$ gearing with it in different planes, as 15 shown. The pinion H^{20} is driven from the spindle H^6 of the paste-wheel through the medium of the spur-pinions $H^{16} H^{23}$.

The action of the pasting device is as follows: The paste-wheel projects over the 20 folder, its edge carrying the paste being in the line of movement of the edge of the paper to be pasted, such edge protruding through the slit E^6 above the surface of the folder E . Before the paper edge reaches the blade E^8 25 it comes into contact with the edge H^9 of the rotating paste-wheel H^3 , a flange H^{24} , secured to the folder E , serving to incline the edge of the paper over, so that it comes into intimate contact with the edge H^9 of the paste-wheel 30 and is completely pasted. As has been shown, the rotation of the paste-wheel H^3 causes the rotation of the grinding-rollers $H^{16} H^{17} H^{18}$, and these rollers serve to crush any lumps or small particles in the paste and 35 insure that the paste is fed to the wheel H^3 in a uniform condition.

The finished continuous length of cigarette passes from the traveling tape F' into the severing or "cut-off" mechanism. A flared tubular entrance I' guides the cigarette into an 40 aperture I' , formed in a reciprocating carriage I^2 , which moves in an undercut guideway I^3 . Upon the end of the carriage I^2 is mounted a spur-wheel I^4 , to which is bolted a knife-blade 45 I^5 , the curved cutting edge of which is eccentric to the periphery of the wheel. The wheel I^4 itself is mounted eccentrically upon its spindle for a purpose hereinafter described. The 50 knife-blade operates between the aperture I' in the carriage I^2 and a tubular support I^6 , carried upon the carriage in alinement with 55 said aperture I' . The parts are so set that the carriage I^2 commences a forward movement in the same direction and at the same speed as the continuous cigarette at the moment the knife-blade I^5 commences its cut by being brought just above the cigarette-aperture I' . The eccentric mounting of both the 60 spur-wheel I^4 and the spur-wheel I^7 , which 65 drives it, produces a much faster cut-off than could be obtained with spur-wheels of the same dimensions mounted concentrically. The arrangement of the eccentric spur-wheels is such that at the moment the knife I^5 is about to make its cut that point upon the periphery of the spur-wheel I^4 which is near-

est to its spindle is in gear with the driving spur-wheel I^7 , which will necessarily be in gear at that point of its periphery farthest from its spindle, and an accelerated movement 70 of the knife thus takes place, insuring a cleaner cut and reducing to a minimum the danger of buckling the cigarette. The knife-blade being situated above the cigarette-aperture I' comes first into contact with the 75 freshly-pasted joint of the cigarette. The tendency therefore is to press the joint instead of to open it, as would be the case were the blade to operate from beneath the aperture I' . 80

The mechanism for reciprocating the carriage comprises an eccentric I^8 , an eccentric-rod I^9 , coupled to the carriage, and the following gear for turning the spindle upon which the eccentric is keyed: bevel-pinions $I^{10} I^{11}$, spur-pinions $I^{12} I^{13}$, spur-wheel I^{14} , intermediate wheel I^{15} , and driving-wheel I^{16} , the latter being keyed to the main shaft A^3 . The eccentric spur-wheel I^4 receives its motion from the eccentric-wheel I^7 , which is 85 feathered upon its spindle I^{17} and is moved to and fro thereon by means of arms I^{18} , fixed at one end to the spindle of the spur-wheel I^4 , the opposite ends sliding over the spindle I^{17} , one upon each side of the wheel I^7 , which is 90 thus moved to and fro in gear with the wheel I^4 . The spindle I^{17} is driven by the aforesaid spur-pinions $I^{12} I^{13}$, spur-wheel I^{14} , intermediate wheel I^{15} , and driving-wheel I^{16} . The cigarettes after having been severed fall onto a 95 delivery-band or into any convenient receptacle. If it is desired to alter the length of cigarette, it is only necessary to change the driving spur-wheel I^{16} for a larger or smaller one, as the case may be. The intermediate 100 wheel I^{15} , being mounted in a quadrant I^{18} , which is movable about the point I^{19} , can be brought into gear with various sizes of driving-wheel. The main driving-shaft A^3 , which is driven by means of the pulley K , may be 105 in two portions, operatively connected by the clutch L , which may be disengaged, if desired, to allow the picking and compressing mechanisms to run while the other mechanisms are 110 at rest. 115

What we claim as our invention, and desire to secure by Letters Patent, is—

1. In a cigarette-making machine the combination of a picking-roller, a hopper pivotally mounted upon the axle of such roller so 120 that a portion of the periphery of the roller forms a bottom to the hopper, a support in which the roller is mounted and means for oscillating the hopper and rotating the roller, substantially as set forth. 125

2. In a cigarette-making machine the combination of a picking-roller, a hopper pivotally mounted upon the axle of such roller so 130 that a portion of the periphery of the roller forms a bottom to the hopper, pins or teeth on the periphery of the roller, a roller journaled at the base of the hopper so that its pe-

riphery is just clear of the teeth on the picking-roller, a support in which the several parts are mounted, and means for oscillating the hopper and rotating the picking-roller, substantially as set forth.

3. In a cigarette-making machine the combination of a slow-speed picking-roller, a hopper pivotally mounted upon the axle of such roller so that a portion of the periphery of the roller forms a bottom to the hopper, pins or teeth on the periphery of the roller, a roller journaled at the base of the hopper so that its periphery is just clear of the teeth on the picking-roller, a high-speed picking-roller the teeth of which intercalate with those on the slow-speed picking-roller, a support in which the several parts are mounted and means for oscillating the hopper and rotating the picking-rollers, substantially as set forth.

20 4. In a cigarette-making machine feeding and disintegrating mechanism comprising a conveyer-band, feed-rollers situated in proximity to the band so that they receive tobacco therefrom, a high-speed picking-roller having pins upon its periphery situated beneath the feeding-rollers, a hopper beneath the picking-roller, means for oscillating the hopper, a slow-speed picking-roller situated so that a portion of its periphery forms a bottom to the 25 hopper, a roller journaled at the base of the hopper and operating to pack the tobacco upon the teeth of the slow-speed picking-roller, a high-speed picking-roller the teeth of which intercalate with those on the slow-speed picking-roller, a support in which the several parts are mounted, and means for driving the conveyer-band and the rollers, substantially as set forth.

5. In a cigarette-making machine the combination of a traveling band, a presser-roller above the band with its lower surface adjacent thereto so that it compresses tobacco carried by the band in a vertical plane, endless compressing-bands with approximately 40 vertical sides operating to compress the tobacco laterally, a cover-plate between the presser-roller and the compressing-bands, grooved filler-forming rollers situated between the compressing-bands and means for 45 driving the pressing-bands, the presser-roll,

the filler-forming rollers, and the compressing bands, substantially as set forth.

6. In a cigarette-making machine, the combination of a paste-reservoir, a weighted float within the reservoir, grinding-rollers within 55 the reservoir, means for operating the rollers, a slot in the wall of the reservoir near the base thereof, a pasting-wheel in the reservoir, part of said wheel protruding through the slot, scrapers attached to the reservoir and 60 arranged to operate on the top and bottom surfaces of the pasting-wheel, a scraper arranged to operate upon the pasting edge of said wheel and means for driving the pasting-wheel, substantially as set forth.

65 7. In a cigarette-making machine a "cut-off" device comprising a carriage, a spindle mounted in the carriage, a spur-wheel eccentrically mounted on the spindle, a knife-blade secured to the spur-wheel, a second spindle 70 mounted upon the frame of the machine, a spur-wheel eccentrically mounted upon the second spindle and gearing with the spur-wheel on the first spindle and means for driving the spindles and for reciprocating the 75 carriage, substantially as set forth.

8. In a cigarette-making machine a "cut-off" device comprising a carriage, a spindle mounted on the carriage, a spur-wheel eccentrically mounted on the spindle, a knife-blade 80 secured to the spur-wheel at a point remote from the spindle, a second spindle mounted upon the frame of the machine, a spur-wheel eccentrically mounted upon the second spindle and capable of lateral motion thereon, said 85 spur-wheel gearing with the spur-wheel on the first spindle, arms upon the carriage operating to effect the lateral movement of the spur-wheel on the second spindle, means for reciprocating the carriage, and means for 90 driving the second spindle, substantially as set forth.

In testimony whereof we have signed our names to this specification in the presence of two subscribing witnesses.
